**COMBINED DIAL AND HANDS FOR A CLOCK OR
SIMILAR ARTICLE**

**Robert A. Weiss, Flossmoor, Ill., assignor of one-half to
Betty J. Weiss, Flossmoor, Ill.**

Application February 2, 1954, Serial No. 28,795

Term of patent 14 years

(Cl. D42—1)

To all whom it may concern:

Be it known that I, Robert A. Weiss, a citizen of the United States, residing in the village of Flossmoor, in the county of Cook and State of Illinois, have invented a new, original, and ornamental Design for a Combined Dial and Hands for a Clock or Similar Article, of which the following is a specification, reference being had to the accompanying drawing, forming a part hereof.

The figure is a perspective view of a combined dial and hands for a clock or similar article, showing my new design.

I claim:

The ornamental design for a combined dial and hands for a clock or similar article, substantially as shown.
